UNITED STATES PATENT OFFICE.

LE ROY WILLOUR, OF ASHLAND, OHIO.

FLUSH-VALVE.

1,100,110.

Specification of Letters Patent. Patented June 16, 1914.

Application filed June 24, 1913. Serial No. 775,540.

To all whom it may concern:

Be it known that I, LE ROY WILLOUR, a citizen of the United States, residing at Ashland, in the county of Ashland and State of Ohio, have invented certain new and useful Improvements in Flush-Valves, of which the following is a specification.

My invention relates to improvements in valve structures, which are so timed in their operation that they will discharge, upon being actuated, a predetermined amount of liquid, such as water or the like, and has particular reference to a valve of this character adapted to be used as a substitute for the well-known flush tank of a water closet, such flush tank being ordinarily provided with a discharge valve controlled by float means.

An important object of this invention is to provide means of the above mentioned character, which are simple in construction, formed of few parts, compact, and neat in appearance.

Other objects and advantages of this invention will be apparent during the course of the following description.

In the accompanying drawings forming a part of this specification and in which like numerals are employed to designate like parts throughout the same, Figure 1 is a central vertical sectional view through the entire apparatus, parts being shown in elevation, Fig. 2 is a transverse sectional view taken on line 2—2 of Fig. 1, Fig. 3 is a side elevation of a slightly different form of the invention, and, Fig. 4 is a transverse sectional view taken on line 4—4 of Fig. 3.

In the drawings, wherein for the purpose of illustration is shown a preferred embodiment of my invention, attention being called to Figs. 1 to 4 inclusive, the numeral 5 designates a main shell or casing, having one side thereof formed open and normally closed by a removable cover or plate 6, detachably connected therewith by means of screws 7, there being suitable packing 8 preferably arranged between these parts to make a water tight joint. At its upper end each main shell or casing 5 is provided with an inlet pipe 9, to be connected with a water supply pipe (not shown). The inlet pipe 9 in Fig. 1, is provided with a cut off valve 10, whereby the supply of water to the main shell or casing 5 may be controlled.

Disposed below and adjacent the discharge end of the inlet pipe 9 in Fig. 1 is a hori-

zontal turbine or water wheel 11, while in the second form of the invention, as more clearly shown in Fig. 3, the numeral 12' designates a vertical paddle or water wheel. 60 The water wheels 11 and 12' are rigidly mounted upon rotatable shafts 12, journaled through bearings 13. In Fig. 1 the shaft 12 is vertically arranged, while in Fig. 3 it is shown as horizontally arranged. Rigidly 65 mounted upon each of the shafts 12 is a worm 14, engaging a gear wheel 15. This gear wheel is provided centrally thereof with an opening for receiving a stub-shaft or trunnion 16, preferably cast integral with one wall of the casing 5. Rigidly connected with one face of the gear wheel 15 and preferably cast integral therewith is a lateral annular control flange 18, provided with a recess 19, as shown.

Connected with the lower end of each of the casings 5 is an outlet pipe 20, the inlet end of which is provided with a recess 21, serving as a valve seat for a reciprocatory valve 22, which controls the passage of the 80 water from the main shell or casing 5 into the outlet pipe 20. Pivotaly connected, as shown at 23, with the valve 22, Figs. 1 and 2, is a reciprocatory rod 24, the upper end of which operates within a suitable guide 25, 85 as shown. In Figs. 3 and 4, a rod 48 is pivoted to the valve 22, at 23, and operates through a guide bracket 49. Rigidly connected with the reciprocatory rod 24 or 48 and preferably cast integral therewith is a 90 lateral extension or finger 26, arranged near and spaced from the upper end of the rod 24. When the rod 24 is elevated, the lateral extension or finger 26 is adapted to ride upon the periphery of the annular flange 18, thereby holding the valve 22 unseated until the gear wheel 15 has made a complete revolution, at which time the lateral extension or finger 26 will again enter the recess 19.

In Figs. 1 and 2, I have shown independently operated means to raise or unseat the valve 22, comprising a bell-crank lever 27, arranged within the outlet pipe 20 and pivoted to a lug 28 or the like. The bell-crank lever 27 is swung by a reciprocatory rod 29, carrying at its outer end a push button 30, arranged to compress a coil spring 31.

In the form of the invention shown in Figs. 3 and 4, the valve 22 is raised or unseated by a cam 32, rigidly mounted upon a 110 rock-shaft 33, which is journaled through a horizontal sleeve 34. The rock-shaft 33 is

turned by a crank 35, having connection with a coil spring 36 which serves to return the same to its normal position.

The operation of the apparatus is as follows:—To flush the bowl, the rod 29 or crank 35 is moved to unseat the valve 22, and raises the rod 24 or 48 so that the laterally extending lug 26 is moved out of the opening 19. The water which always fills the main shell or casing 5, to the exclusion of the air, will now pass through the discharge pipe 20, whereby the flow of water through the inlet pipe 9 into the upper end of the main shell or casing will effect the rotation of the turbine or paddle wheel 11. As soon as the lug 26 engages the periphery of the control flange 18, the rod 29 or crank 35 may be released. The paddle or water wheel is continuously rotated during the passage of water through the main shell or casing 5, and such operation continues until the gear or gear wheel 15 has made a complete revolution, at which time the lug 26 will again drop within the opening 19, thus automatically returning the valve 22 to its seat and cutting off the supply of water to the discharge pipe 22. Particular attention is called to the fact that the valve 22 controls the passage of the water through the outlet pipe 20 and not through the inlet pipe 9, whereby when this valve is seated the main shell or casing 5 will be completely filled with water to completely exclude the air therefrom. It has been found that by thus excluding the air from the operating parts of the apparatus the same will not near so rapidly corrode or rust.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having described my invention, I claim:—

1. In apparatus of the character described, the combination with a main shell provided with an upper inlet and a lower outlet, of a rotatable shaft mounted within the upper portion of the main shell, a water wheel connected with the rotatable shaft and disposed below and adjacent the inlet, a worm connected with the rotatable shaft, a

gear wheel rotatably mounted within the main shell and driven by the worm, and provided upon one face thereof with a control flange having a recess formed therein, a reciprocatory rod provided with a lateral extension to engage with the control flange, a valve to control the passage of the water through the outlet and connected with the rod, and independently operated means to unseat the valve.

2. In apparatus of the character described, the combination with a main shell provided with inlet and outlet openings, of a valve to control the passage of water through the main shell, a reciprocatory rod connected with the valve and provided with a lateral extension, a gear wheel rotatably mounted within the main shell and provided upon one face thereof with a substantially annular laterally extending flange arranged inwardly of and spaced from the periphery of the gear wheel to engage with said lateral extension and having an opening formed therein to receive said lateral extension, and means including a water wheel to rotate the gear wheel.

3. In apparatus of the character described, the combination with a main shell provided with inlet and outlet openings, of a valve to control the passage of the water through the outlet opening, an upstanding rod arranged within the main shell and provided with a lateral extension, a gear wheel rotatably mounted within the main shell upon one side of the upstanding rod and provided upon one face thereof with a substantially annular control flange formed integral therewith and arranged within and spaced from the periphery of the gear wheel and provided with a recess, a substantially horizontal shaft arranged within the main casing near and above the gear wheel, a worm carried by the substantially horizontal shaft and engaging the gear wheel, and a substantially vertical water wheel connected with the substantially horizontal shaft and arranged adjacent the inlet opening.

In testimony whereof I affix my signature in presence of two witnesses.

LE ROY WILLOUR.
